UNITED STATES PATENT OFFICE.

BERNARD KRÄMER, OF ALTBRESCHEINBURG, GERMANY, ASSIGNEE TO GENERAL ELECTRIC COMPANY, A CORPORATION OF NEW YORK.

STARTING MECHANISM FOR HIGH-COMPRESSION ENGINES.

1,131,387.

Specification of Letters Patent.

Patented Nov. 9, 1915.

Application filed August 15, 1912. Serial No. 715,219.

Total weight it may concern:

Be it known that I, Bernhard Krämer, subject of the Emperor of Germany, and residing in Charlottenburg, Germany, have invented certain new and useful Improvements in Starting Mechanism for High-Compression Engines, of which the following is a specification.

The present invention relates to starting mechanism for high compression engines, that is to say engines wherein a charge of substantially pure air is heated by compression to a temperature above the ignition temperature of the injected fuel so that the latter upon being introduced into the compression space, is fired immediately. In such engines the pressures are very high, often exceeding 1000 pounds per square inch. To start them it is necessary to utilize high pressure air or other fluid from a suitable reservoir or tank and control its admission by valve means.

My invention has for its object to improve the construction and operation of such starting mechanisms, and in particular to permit of starting the engine quickly without having to actuate by hand relatively large valves which are subjected to heavy pressures and therefore difficult to move quickly, or without cutting the fuel or needle valves out of service.

For a consideration of what I believe to be novel in my invention, attention is directed to the accompanying description and claims appended thereto.

In the accompanying drawings which are illustrative of one of the embodiments of my invention, Figures 1 and 2 are sections through the starting valve mechanism, and 3 a section, being taken at right angles to each other; Fig. 4 is a plan view of said mechanism, and Fig. 5 is a part of a high compression internal combustion engine.

Referring first to Fig. 4, 5 indicates a part of the main frame of the engine that is preferably hollow and acts as a receiver for the scavenging air, said air being utilized to clear the working cylinders of the burned products of combustion. Air for this purpose is supplied by a double acting scavenging pump 6 which is controlled by three starting cylindrical valves 7. Only one of these valves is shown, the other being located directly under the starting valve mechanism

to be described later. 8 and 9 indicate the main working cylinders of the engine, which are also located in the receiver 5 so as to avoid the losses incident to long passages, pipes, etc. Only two cylinders are shown, but it is to be understood that as many such cylinders may be provided as are desired. Ordinarily, but not necessarily, less than the total number of cylinders will be provided with air starting means, the number depending upon the character of the service for which the engine is intended. 10 indicates the casing of the starting valve means and extending therefrom are pipes 11 and 12, of suitable size, the former leading to a suitable place in the cylinder 8 and the latter to a suitable place in the cylinder 9. From the casing also extend pipes 13 and 14 of suitable size for conveying compressed air, commonly referred to as the "blast air", to the cylinders for injecting fuel into them. This fuel may with advantage be what is commonly termed crude oil. Each of these pipes terminates in a fuel pulverizer, atomizer, or other form of injector 15 of suitable construction. It is to be understood that these pulverizers are provided with fuel valves operated by any suitable mechanism which is not here illustrated because unnecessary to an understanding of the invention.

Where each of the cylinders is provided with only one working piston the pulverizer will be mounted in the head of the cylinder, but where each is provided with two oppositely moving working pistons said pulverizer will be carried by the cylinder and suitably positioned to inject the fuel between said pistons. The pistons are connected to the main shaft by suitable connecting rods. The scavenging pump 6 and the rotary valves 7 are also mechanically connected to the main shaft. The starting valve mechanism is operated by a suitably disposed shaft 16 having a hand wheel 17 for turning it. 19 indicates the tank containing air under high pressure for starting and leading therefrom to the starting valve mechanism is a pipe 20 having a shut off valve 21. 22 indicates the tank containing compressed air for supplying the blast for injecting fuel. It is connected to the casing 10 by a pipe 23 in which is located a hand actuated shut off valve 24.

Referring to Figs. 1 and 2, 10 indicates the casing of the starting valve mechanism. It is provided with a passage 28 that com-

2

municates by the pipe 20 with the starting tank 19, and also with a passage 29 that communicates by the pipe 23 with the air blast tank 22. Situated in the passage 29 is a check valve 30 that moves in response to fluid under pressure and also in response to the pressure of the coiled compression spring 31. Its function is to cut off the blast air when the air starting mechanism is in operation. Below the valve is a vertical passage 32 which terminates at its lower end in a transverse passage 33 communicating with the pulverizer 15. This passage is shown in dotted lines Figs. 3 and 4. It is to be understood that blast air for the other working cylinders passes thereto and is controlled by any suitable means. The upper end of the spring 31 is seated in an adjustable hollow nut or plug 34 which 10 is provided with lateral ports at its lower end opening into the chamber 35. This chamber is connected by a passage 36, shown in dotted lines, with a controlling valve to be described later. The chamber 20 and passage carry off leakage air from above the valve. The plug 34 is provided with a screw threaded cap that prevents the escape of air through the hole in the top thereof, which hole is arranged to receive a wrench. 25 Located in the right hand side of the casing is a controlling valve means comprising valves 37 and 38 which are mounted on the same stem; each valve being provided with its own seat. The upper seat is formed on 30 the upper end of the fixed sleeve 39 and the lower one on the upper end of the sliding tube 40, which also forms an actuator to open the upper valve 37. In the sleeve 39 are radial ports communicating with the annular chamber 41, the latter opening into the passage 36 leading to the check valve. The tube 40 is provided with an escape or vent port 42 near its lower end and also with a plug 43, the latter engaging the lower 35 abutment of the compression spring 44. The abutment is made in the form of a tubular guide which is forked to receive the roller 45. The casing is vented above the guide to permit the escape of air from the tube. 40 The upper valve 37 is normally held closed by the compression spring 46 contained in a suitable hollow plug. As shown the valve 37 is open and the valve 38 closed. This means that air under pressure can flow 45 from the supply passage 29 and small passage 47 past the valve 37 into the sleeve 39 and through its ports into the chamber 41 and passage 36 to the upper side of the check valve 30 in the path of the blast air. 50 As soon as this happens the fluid pressures on opposite sides of said valve are equalized and the spring 31 closes it and therefore the blast air cannot flow from the tank 22, pipe 23 and passage 29 to the pulverizers. 55 The advantage in cutting off the supply of

blast air at this point resides in the fact that it then becomes unnecessary to modify in any way the action of the needle valve of the pulverizer or its actuating mechanism; in other words cut it out of service. This 70 results in a material mechanical simplification besides decreasing the original cost and that of maintenance.

The next thing to consider is the means for actuating the controlling valve means 75 for the check valve, i. e. valves 37 and 38. 16 indicates a horizontal shaft that is supported in suitable bearings. On the shaft is a cam 50 of the proper shape which as it is turned raises and lowers the tubular 80 actuator 40 and with it the valves 37 and 38. On the cam I have shown for convenience three small circles indicating different positions of the parts. When the left hand circle is under the axis of the tube 40 the 85 parts are in the working or normal running position of the engine. When the second circle is under said axis, as shown, the parts are in the position for stopping the engine and when the right hand circle is under said 90 axis, the parts are in position for starting. On the far end of the shaft 16 is a crank 51 that fits into a sliding block 52, the latter being carried and guided by the fork at the 95 end of the lever 53. The lever is pivoted at 54 and on the left hand end is provided with a fork that engages shoulders 55 on the reciprocating and rotary sleeve 56. Between the arms of the fork and said shoulders are 100 rollers 57 to reduce friction. In broken and dotted lines are indicated the positions of the centers under the "working," "stopping" and "starting" positions above referred to.

Turning to Fig. 1 it will be seen that the upper end of the sleeve which is splined on the rotary shaft 58 is provided with a suitable cam 59, said cam operating the starting valves, as will be seen later. Under normal running or working conditions the 110 cam is idle, merely rotating with the shaft 58 which drives one of the rotary valves for the scavenging pump and itself is geared to the main shaft.

61 indicates a double seated starting valve 115 controlling the passage of high pressure air to the cylinder 8. It is provided with a stem 62 that makes a close sliding fit in an inclosing sleeve; the general arrangement being such as to prevent leakage. The 120 lower end of the stem rests on a tubular movable abutment 63 which has a side port to permit air to escape through a corresponding port in the casing. Between a 125 wall of the casing and the abutment is a compression spring 64 that tends at all times to force the abutment downward. The abutment is forked to receive a roller 65 that engages the cam 59 when it is raised. The particular engine described is designed 130

to operate on the two cycle plan and the cam should be shaped accordingly. The arrangement is not necessarily limited thereto. It is to be understood in using this apparatus that the main shaft is first turned by a bar or other means until the cam 59 is brought under one of the roller supports preparatory to operating the starting handle 17 and 18, fig. 18. Assuming that the preliminaries have been properly attended to, the hand wheel 17 is turned anti-clockwise thereby raising the cam 59. This will raise one of the starting valves (both valves being alike) and the air will pass from the passage 28 through a valve to the chamber 66, the latter communicating with the pipe 11 or 12, as the case may be. The high pressure air thus admitted to one cylinder starts the engine which turns the shaft until the cam 59 raises the next air starting valve and so on. After a few turns the hand wheel is rotated in a clock-wise direction until the cam sleeve 56 drops and the roller 45 of the controlling valve registers with the circle indicating the running position. As a result of this latter operation the roller 45 and its carrier are moved downward permitting the tube 40 to likewise move and seat the valve 37 and unseat the valve 38. Air from above the check valve 30 then escapes by the passage 36 chainbar 41, ports in the sleeve 33, tube 40, port 42 to atmosphere or other point of low pressure. The blast pressure in passage 29 then opens the check valve 30 and said air flows to the pulverizers by passages 32, 33 and pipes 13 and 14.

Looking at it from one point of view the valves 37 and 38 and coöperating parts form a controlling valve means to control the operation of the pressure actuated valve 30 which I therefore designate as a pilot valve to distinguish from the numerous other valves, and coöperating therewith is an agent or actuating means, such for example as the handle 17 and shaft 16 etc. which actuates said controlling valve and also the starting valves 61. In the former case the actuating means acts directly on the valves 37 and 38 and in the latter case indirectly on the valves 61 through the instrumentality of the lever 53 and parts associated therewith.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States is:

1. In an engine of the character described, the combination of a working cyl-

inder, means for admitting fluid under pressure thereto for starting purposes, a starting valve for controlling said fluid, an injector, a normally open fluid actuated valve controlling the admission of fluid to the injector, and means for controlling the starting and fluid actuated valves.

2. In an engine of the character described, the combination of a working cylinder, a source of fluid under pressure for starting purposes, a valve controlling its admission to the cylinder, a conduit supplying fluid to the cylinder for normal working purposes, a normally open valve for controlling it, and means which causes the second valve to close when the first is opened.

3. In an engine of the character described, the combination of a working cylinder, a conduit supplying fluid under pressure thereto for starting, a valve in said conduit, a second conduit supplying the blast to inject fuel into the cylinder, a pressure controlled valve in the second conduit, and means which directly actuates the first valve and controls the second valve.

4. In an engine of the character described, the combination of a working cylinder, a conduit supplying an elastic fluid thereto under pressure for starting purposes, a starting valve controlling the admission of said fluid to the cylinder, a second conduit supplying a blast of air to the cylinder for injecting fuel, a pressure actuated valve in the second conduit, a pilot valve means controlling the second valve, and means which activates the pilot and starting valves.

5. In an engine of the character described, the combination of a working cylinder, a conduit supplying starting fluid thereto, a controlling means therefor, a second conduit for supplying injecting fuel to the cylinder, a normally open fluid actuated valve in said second conduit, and a single means for moving the controlling means to operating position and admitting fluid pressure to close the normally open valve.

6. In an engine of the character described, the combination of a working cylinder, a conduit supplying starting fluid to the cylinder, a controlling means therefor, a second conduit supplying fluid for injecting fuel into the cylinder, a pressure actuated valve in the second conduit, and a means for regulating the action of the controlling means and also of said valve.

7. In an engine of the character described, the combination of a working cylinder, conduits supplying fluid to the cylinder for starting and fuel injecting purposes, a mechanically actuated valve in one of the conduits, a fluid pressure actuated valve in the other conduit, a pilot valve for the latter, cams for positively actuating the starting and pilot valves, and means for positively moving the cams into operative position.

with respect to the valves whereby the starting valve is opened and the pressure actuated valve closed.

8. In an engine of the character described, the combination of a working cylinder, a conduit supplying fluid thereto to inject fuel, a pressure actuated controlling valve in the conduit, a pilot valve therefor, and means for moving the pilot valve in one direction to equalize the fluid pressures on opposite sides of the controlling valve and permit it to close, and in the opposite direction to establish a difference in pressure on opposite sides and permit it to open.

15 9. In an engine of the character described, the combination of a working cylinder, conduits supplying fluid thereto for starting and fuel injecting purposes, valves for the conduits, a casing therefor, a constantly rotated cam for the starting valve, a manually operated cam for controlling the action of the injecting valve, a means movable with the second cam for moving the first into and out of operative relation with respect to the

25 starting valve.

10. In an engine of the character described, the combination of a plurality of working cylinders, conduits supplying compressed fluid thereto for starting and injecting purposes, a starting valve in each of the conduits conveying starting fluid, a normally open valve that is common to all of the cylinders for controlling the supply of fuel injecting fluid, a means for actuating 30 the starting valves, a means controlling the injecting valve, and a single mechanism for moving the actuating means to operative position and operating the controlling valve.

35 11. In an engine of the character described, the combination of a working cyl-

inder, a conduit supplying starting fluid thereto, a valve therein, a cam for operating the valve, a starting lever for moving the cam into and out of operative position with relation to the valve, a conduit supplying injecting fluid to the cylinder, a normally open valve therein, and means controlled by the starting lever for closing said last named valve when the cam is moved to operative

45

50

12. In an engine of the character described, the combination of a working cylinder, a conduit supplying starting fluid thereto, a valve therein, a cam for operating the valve, a starting lever for moving the cam into and out of operative position with relation to the valve, a conduit supplying injecting fluid to the cylinder, a normally open fluid actuated valve therein, means controlling the admission of actuating fluid thereto, and means controlled by the starting lever for operating the first named means when the cam is moved to operative position.

55

60

13. In an engine of the character described, the combination of a working cylinder, tanks containing fluid under pressure, one of said tanks supplying starting fluid to the cylinder and the other injecting fluid, separate controlling valves for the starting and injecting fluid, the valve controlling the injecting fluid being normally open, and means acting to close the injecting valve when the starting valve is open.
